UNITED STATES PATENT OFFICE

ROSS W. JUDSON, OF DETROIT, MICHIGAN, ASSIGNOR TO CONTINENTAL MOTORS CORPORATION, OF DETROIT, MICHIGAN, A CORPORATION OF VIRGINIA

INTERNAL-COMBUSTION MOTOR

Application filed May 14, 1926. Serial No. 109,046.

My invention relates to an improved construction of internal combustion motors of the sleeve type, that is to say the type where a movable sleeve surrounds each piston of the motor to enclose the corresponding firing chamber, the sleeve being movable and provided with ports through it to control the intake of combustible mixture and the efflux of exhaust gases. In motors of this type, the bore of the sleeve preferably forms the bore of the corresponding cylinder and in fact comprises the cylinder as far as containing and restraining the working fluid is concerned. To mount the sleeves in proper position for use, they are preferably placed in somewhat larger bores in the cylinder block. Means are provided for moving the sleeves in the bores in the cylinder block to open and close the intake and exhaust ports at the proper time, as required by the cycle of operation of the motor. Motors of the kind under consideration usually require water cooling to prevent their overheating and this is accomplished by water jacketing the bores of the cylinder block in one way or another.

By my invention, I provide that the bearing surface of the pistons shall be at all times against the bores of the corresponding sleeves, and I protect the bores in the cylinder block from the action of the gases in the firing chambers by suitably constructing the sleeves and head of the motor, and I am therefore able to construct the cylinder block of metal not well adapted to stand the relatively great wear experienced between the pistons and their co-operating bores or the high temperatures developed in the firing chambers. For example I prefer to construct the sleeves of steel and the cylinder block of light weight metal, for example aluminum or aluminum alloy. The movement of the sleeves relatively to the cylinder block is small and much slower than the piston movement and since the bores of the cylinder block are protected by the sleeve, the relatively soft material of the cylinder block forms bearing surfaces for the sleeves that are entirely satisfactory and the necessity for steel or iron liners in the bores in the cylinder block is thus avoided.

By my invention I further provide a novel construction of water jacket, by which the water spaces are open towards the exterior of the cylinder block casting when it is made, thus permitting the water spaces to be formed in the mold itself without the use of cores, or at most the use of green sand cores as distinguished from baked cores. In cylinder blocks as heretofore constructed, it has been necessary to use baked cores of greater or lesser complexity and at considerable expense on account of the forming of the inner and outer walls of the water jacket integrally in the same casting. To enclose the water spaces around the cylinder bores, I employ sheet metal plates, for example iron or steel, securely fastened to the upper and lower edges of the cast metal structure containing the water spaces, for example by suitable screws and to make the joints tight, packing or cement may be employed.

To facilitate entirely protecting the cylinder bores from the working fluid by means of the sleeves, which I find is desirable, I extend the cylinder bores and sleeves appreciably beyond the clearance spaces in the cylinders at their head ends and form the cylinder head with projecting cylindrical extensions fitting the bores of the sleeves above the pistons. The cylinder head is preferably formed with water spaces in alignment with and opening into the water spaces in the cylinder block, to cool the cylinder head and assist in maintaining the sleeves in relatively cool condition. I find it convenient to secure the upper edge of the enclosing sheet metal to the outer edge of the cylinder head and the lower edge of the sheet metal to the lower outer edge of the cylinder block, thus enclosing by a single sheet metal covering the water spaces in both the cylinder block and the cylinder head.

My invention will best be understood by reference to the accompanying drawings showing a preferred embodiment thereof in which

Fig. 1 illustrates a four cylinder motor in accordance with my invention, in longitudinal, vertical sectional view,

Fig. 2 shows in side elevation a part of the

cylinder block with the enclosing sheet metal in place.

Fig. 3 is a horizontal, sectional view through the parts shown in Fig. 1 taken along the line 3—3.

Fig. 4 is a horizontal, sectional view taken through the sleeve operating shaft.

Fig. 5 is a diagrammatic view illustrating the relation of the intake ports, and

Fig. 6 is a diagrammatic view illustrating the relation of the exhaust ports.

Similar numerals refer to similar parts throughout the several views.

As shown in Fig. 1 my improved motor construction consists of a cylinder block 10 of soft cast metal, preferably aluminum or aluminum alloy provided with parallel bores 11, 12, 13 and 14 for receiving with a sliding fit the sleeves 15, 16, 17 and 18 respectively, 15 said sleeves being made preferably of iron or steel. The said bores and sleeves extend considerably above the extreme upper positions of the pistons 19, 20, 21 and 22 mounted to reciprocate freely in the bores of said 20 sleeves respectively, and I provide a cylinder head 23, preferably of cast iron with cylindrical extensions 24, 25, 26 and 27 fitting respectively with a sliding fit in the bores 25 of the upper ends of the said sleeves, the inner ends of said extensions being formed to afford desired clearance or compression chambers between said inner ends and the upper ends of the pistons in their uppermost position, and being threaded as indicated to receive 30 suitable spark plugs for firing the charges in the working cylinders. The outer ends of the extensions 24, 25, 26 and 27 are provided with flanges 24a, 25a, 26a and 27a to secure the cylinder head to corresponding flanges extending from the upper 35 ends of the bores in the cylinder block. To water jacket the extensions 24, 25, 26 and 27, spaced walls 24b, 25b, 26b and 27b are provided on the cylinder head forming water 40 spaces between them and the said extensions 45 and leaving clearance spaces for the reception of the spark plugs above referred to. The walls 24b, 25b, 26b and 27b are extended outwardly and laterally of the cylinder head 50 and terminate in a downwardly extending flange 28 in line with a shouldered flange 29 on the lower end of the cylinder block. The flange 28 is spaced from the flanges on the upper end of the cylinder block to define 55 water spaces around the walls of the bores of the cylinder block and the water passages in the head are thus in free and unrestricted communication with the water passages surrounding the walls of the bores of the cylinder block. To enclose the water spaces referred to, I secure sheet metal plates 30 to the flanges 28 and 29 in any suitable manner, for example by screws as indicated, the said 60 plates preferably terminating at the ends of 65 the cylinder block where they overlap and

are secured to ribs 31, 31 of the cylinder block provided for that purpose. The joints between the sheet metal plates 30 and the head and cylinder block may be made tight in any desired manner, for example by suitable packing or cement.

The lower end of the cylinder block is preferably a plane surface resting on the corresponding upper surface of a crank case 32 provided with bearings 33, 33 supporting a 70 crank shaft 34, the cranks of which are connected by connecting rods 35, 35 with the pistons.

As shown in Fig. 3, the cylinder block 10 is provided with intake ports 36, 37, 38 and 80 39 into the corresponding bores 11, 12, 13 and 14, and also exhaust ports 40, 41, 42 and 43 in the opposite sides of the walls of the bores in the cylinder block. Suitable communicating passages are formed in the cylinder block connected with the said ports as indicated, terminating in outer connection rings 36a, 37a, 38a and 39a for the intake ports, to which the intake manifold may be conveniently attached, and similar connection rings 40a, 41a, 42a and 43a for the exhaust ports to which the exhaust manifold 90 may be conveniently attached.

As illustrated in Figs. 2 and 3 the said connection rings may be conveniently shouledered and the cover plates 30 are preferably apertured as indicated at 40b, 41b, 42b and 43b to tightly enclose the water spaces and at the same time present the connection rings 95 for attachment with the corresponding manifolds, the connection rings, plate apertures and ports shown in Fig. 2 being for the exhaust, it being understood that the construction employed for the intake connection rings is the same.

The sleeves 15, 16, 17 and 18 have communicating ports formed through them for registry at the proper times during the cycle of operation of the motor, with the intake and exhaust ports above referred to, and while any desired form of operating mechanism may be used to move the sleeve to secure such registry of said ports, I illustrate for example one type of operating mechanism as follows. The sleeves 15, 16, 17 and 18 have extending outwardly from their lower ends lugs 15a, 15a, 16a, 16a, 17a, 17a, 18a, 18a, between which are respectively pivotally connected at one end, the sleeve connecting rods 44, 45, 46 and 47, the pivotal connections 110 of these connecting rods extending vertically and permitting motion of the connecting rods relatively to the corresponding sleeves in but one direction, that is angularly about their pivotal connections.

As shown in Fig. 4, the crank shaft 34 carries a gear 48 meshing with a gear 49 carried by the sleeve operating shaft 50, the ratio of the said gears being such that the shaft 50 rotates half as fast as the shaft 34.

The shaft 50 is supported in bearings 51, 51 carried by the crank case, parallel with the shaft 34 and at a height corresponding to the mid position vertically of the lugs on the sleeves. The parts just described are assumed to be carried by the part of the crank case removed in Fig. 1 and as a result no attempt is made to illustrate these parts in Fig. 1. The shaft 50 is provided with cranks 52, 53, 54 and 55 on which the other ends of the connecting rods 44, 45, 46 and 47 are respectively mounted, each of said cranks being longer than the width of the corresponding bearing of the connecting rod, as a result of which rotation of the shaft 50 moves the sleeves both angularly and longitudinally, the connecting rods moving longitudinally of the corresponding cranks as required by said angular movement of said sleeves. The motion thus imparted to each sleeve is such that any point on its surface describes a closed curved path which may approach more or less closely to a circular path, depending upon the particular design employed. This movement I find advantageous in connection with controlling the proper opening and closing of the ports without undue motion of the sleeves and effectively lubricating the outer surfaces of the sleeves and the corresponding bores in the cylinder block.

In Figs. 5 and 6 the relation of the ports is illustrated diagrammatically for the relation of the pistons illustrated in Fig. 1, assuming that the piston 19 is about to begin its firing or working stroke, the piston 20 is beginning its exhaust stroke, the piston 21 is beginning its compression stroke and the piston 22 is beginning its intake stroke, the firing order assumed for said pistons being 19, 21, 22, 20. In Fig. 5 the ports 15b, 16b, 17b and 18b are the intake ports formed in the sleeves 15, 16, 17 and 18 respectively, which ports have motions indicated by the corresponding dotted closed curves, the corresponding intake ports in the cylinder block being indicated at 36, 37, 38 and 39. Fig. 6 similarly shows exhaust ports 15c, 16c, 17c and 18c in the sleeves 15, 16, 17 and 18 respectively having paths of motion represented by the dotted closed curves to co-operate with the exhaust ports 40, 41, 42 and 43 respectively in the cylinder block.

By my invention I produce a construction of motor that not only has the advantage of smoothness of operation of the sleeve type motor but the additional advantages of lightness and cheapness of construction.

While I have shown my invention in the particular embodiment above described, it will be understood that I do not limit myself to this exact construction as I may employ equivalents known to the art at the time of the filing of this application without de-

parting from the scope of the appended claims.

What I claim is:

1. In an internal combustion motor, the combination of a cylinder block having bores therein provided with separated walls, a flange connecting said walls at one end and extending outwardly radially therefrom, a head enclosing the other ends of said bores and having a flange extending outwardly radially therefrom, and a sheet metal casing secured to said flanges to enclose a water space around said walls, said casing comprising a plurality of sheets of metal, and said cylinder block having longitudinal ribs extending across its water space to be secured to the edge portions of said sheets. 70 75 80

2. In an internal combustion engine, a cylinder, a sheet metal structure jacketing said cylinder, and a reentrant cylinder head structure for closing the cylinder and provided with a jacket in communication with the cylinder jacket, said cylinder head provided with an extended down-turned flange portion located in substantially the same plane as the outer face of the cylinder, said sheet metal structure arranged to be secured to the down-turned flange of the cylinder and to the cylinder structure. 85 90

3. In an internal combustion engine, a cylinder provided with outwardly projecting portions, a reentrant cylinder head structure comprising spaced inner and outer walls forming a jacket, the inner wall extended outwardly to overlie the outer wall and provided with a down-turned flange spaced outwardly from the outer wall of the cylinder head and located in substantially the plane of the outer face of said cylinder projecting portions, and a sheet metal structure secured to the down-turned flange of the cylinder head and to the outer face of the projecting portions carried by said cylinder. 95 100 105

In witness whereof, I hereunto subscribe my name this 11th day of May, A. D. 1926. 110
ROSS W. JUDSON.
